US00D907050S

(12) **United States Design Patent** (10) **Patent No.:** **US D907,050 S**
(45) **Date of Patent:** **** Jan. 5, 2021**

(54) **MONITOR SUPPORT**

(71) Applicant: **Humanscale Corporation**, New York, NY (US)

D462,969 S 9/2002 Scharer
D486,486 S 2/2004 Jobs
6,695,270 B1 2/2004 Smed

(Continued)

(72) Inventors: **Mesve Vardar**, New York, NY (US);
Fabian Monsalve, New York, NY (US); **Paul Sukphisit**, New York, NY (US)

FOREIGN PATENT DOCUMENTS

CN 301901575 * 5/2012
CN 305203567 * 6/2019

(Continued)

(73) Assignee: **Humanscale Corporation**, New York, NY (US)

(**) Term: **15 Years**

(21) Appl. No.: **29/645,342**

(22) Filed: **Apr. 25, 2018**

(51) LOC (13) Cl. **14-02**

(52) U.S. Cl.

USPC **D14/452**

(58) **Field of Classification Search**

USPC D14/447-452, 336, 341, 371, 373, 374,
D14/375, 376, 377, 126, 127, 128, 129,

D14/239

CPC F16M 11/105; F16M 11/10; F16M 11/048;

(57) **CLAIM**

We claim the ornamental design for a monitor support, as shown and described.

DESCRIPTION

FIG. 1 is a front perspective view of a monitor support illustrating our new design;

FIG. 2 is a rear perspective view thereof;

FIG. 3 is a rear view thereof;

FIG. 4 is a front view thereof;

FIG. 5 is a right side view thereof;

FIG. 6 is a left side view thereof;

FIG. 7 is a top view thereof; and,

FIG. 8 is a bottom view thereof.

The dash-dot lines in the figures show environmental elements that form no part of the claimed design. The dash-dot-dot lines show unclaimed boundaries that form no part of the claimed design.

1 Claim, 8 Drawing Sheets
